WINDOW

Albert H. Weber, Kenosha, Wis., assignor of one-half to Thomas A. Shilka, Kenosha, Wis.

Application April 15, 1933, Serial No. 666,310

1 Claim. (Cl. 20—42)

This invention appertains to window frames and sashes and has for one of its primary objects the provision of novel means for mounting window sashes in the window frames, whereby the sashes can be conveniently disposed for ventilating purposes and whereby the sashes can be readily manipulated and swung into a room to facilitate the cleaning of both faces of the window panes without any inconvenience on the part of 10 the operator.

Another salient object of my invention is the provision of novel spring-pressed guide pins carried by the sashes for traveling movement in the novelty formed sash guide grooves, with keeper recesses in the grooves for receiving said spring-pressed pins for automatically holding the sashes in their preferred adjusted positions.

A further salient object of my invention is the provision of a novel window frame provided with 20 sashes located one above the other with novelly arranged communicating sash guide grooves in said frame for receiving spring-pressed guide pins carried by the sashes, the formation of the guide grooves and pins allowing the sashes to be tilted 25 at a desired angle for ventilating purposes and swung entirely within a room for facilitating the washing of the opposite sides of the window pane.

A further important object of my invention is the provision of novel metallic guide ways located 30 in the grooves for receiving the spring-pressed pins, the guideways being provided with the indentations constituting the keeper recesses for co-operating with the pins to hold the sashes in their adjusted positions.

35 A still further object of my invention is to provide an improved arrangement of window frame and sashes of the above character, which will be durable and efficient in use, and one which can be placed upon the market at a reasonable cost.

40 With these and other objects in view, the invention consists in the novel construction, arrangement and formation of parts, as will be hereinafter more specifically described, claimed and illustrated in the accompanying drawings, in 45 which:

Figure 1 is a vertical longitudinal section through a window frame and window sashes constructed in accordance with my invention, showing the sashes in their superimposed closed position in full line, the view showing one of the sashes swung into the room in dotted lines for washing purposes.

50 Figure 2 is a view similar to Figure 1 showing the sashes in one of their adjusted positions for ventilating purposes.

Figure 3 is an enlarged detail fragmentary horizontal section taken on the line 3—3 of Figure 1 looking in the direction of the arrows illustrating the connecting horizontal groove for the vertical guideways with the keeper recesses formed within the horizontal groove for receiving the spring-pressed pins.

Figure 4 is a view similar to Figure 3 taken on the line 4—4 of Figure 1 looking in the direction of the arrows.

Figure 5 is a view similar to Figures 3 and 4 taken on the line 5—5 of Figure 1 looking in the direction of the arrows, illustrating the formation of the bottom guideway for permitting the sashes to be swung entirely within a room.

Figure 6 is an enlarged detail fragmentary side elevation illustrating the arrangement of the vertical guide grooves and the connecting horizontal groove.

Figure 7 is an enlarged detail side elevation of 75 the bottom fitting or guideway for the guide grooves.

Referring to the drawings in detail, wherein similar reference characters designate the corresponding parts throughout the several views, the 80 letter A generally indicates the window frame and B and C the top and bottom sashes respectively mounted within said window frame.

The sash frame A comprises the side vertical stiles 10, the bottom sill construction 11 and the 85 top lintel construction 12.

In accordance with my invention, I provide a pair of spaced vertically extending guide grooves 13 and 14 in the faces of the stiles 10. These grooves 13 and 14 extend the full length of the 90 frame and the groove 14 at its extreme lower end is provided with an arcuate lower extension 15 which communicates with the lower end of the vertical groove 13. Communicating with both of the lower ends of the grooves 13 and 14 is a comparatively short horizontal groove 16 which facilitates the swinging of the sashes into a room, as will be more fully set forth, and I lay particular stress on the formation of this groove 16 in conjunction with the grooves 13 and 14.

100 The grooves 13 and 14 of each stile are connected at a point intermediate their ends by means of a horizontal groove 17. The inner end of each horizontal groove 17 terminates in short 105 oppositely extending vertical grooves 18 and by referring to the drawings, it will be noted that the inner faces of the stiles have fitted there-against stop strips 19, which are provided intermediate their ends with cut-out portions which form the 110

short grooves 18. Finishing beads or the like 20 can be fitted against the stop strips 19.

One of the salient features of my invention is the provision of novel metallic guideways fitted 5 within the various grooves to form wear and anti-friction faces for the sashes and these metal guideways can be formed in different sections to facilitate the placing thereon within the guide grooves. Thus, by referring to Figure 7, it can 10 be seen that I can provide a bottom metallic section 21 for fitting within the grooves 13 and 14 and curved extension 15 and the horizontal groove 16. Mating with the ends of the fitting 21 are vertical metallic guide strips 22. Short metallic 15 guide strips 23 and 24 are placed in the horizontal grooves 17 between the vertical grooves 13 and 14 and the flanges of the vertical metallic guide pieces are cut at their point of crossing with the horizontal metallic guides 23 and 24, and are 20 curved as at 25 to engage with the flanges of said short metallic guide pieces 23 and 24.

At a point intermediate the ends of the stiles, I provide indentations within the metallic guide strips to form keeper recesses 26, 27 and 28. The 25 keeper recess 26 is located within the vertical groove 13 at its point of communication with the horizontal groove. The keeper recess 27 is located wholly within the horizontal groove between the vertical grooves 13 and 14, while the recess 28 is 30 located in the horizontal groove 17 adjacent to the short vertical grooves 18.

The sashes B and C in their normal positions are arranged one upon the other and their mid-rails 29 and 30 respectively are formed for abutting 35 relation with one another and in such a manner as to form a leak-proof joint. As shown, the top sash B includes the midrail 29, and the top rail 31 and side rails 32. Suitable window panes 33 are carried by said rails. The bottom sash C 40 embodies the midrail 30, the bottom rail 34 and side rail 35 and is also provided with suitable window panes 36.

By referring to Figure 1, it can be seen that both of the sashes are normally arranged for 45 movement in the outer vertical groove 13 and the same are adapted to be held in a closed position by a suitable sash fastener 37.

In accordance with my invention, I provide each of the sashes B and C adjacent to their 50 upper and lower ends and at the side rails thereof with outwardly extending spring-pressed pins 38 and these pins are normally received in and slide within the various grooves heretofore described. The upper spring-pressed pins 38 carried 55 by the lower sash C are received within the keeper recess 26 and when it is desired to ventilate a room, the sash fastener 37 is manipulated and the top of the sash C is pulled inwardly and the sash will swing on its bottom pins 38 as a pivot. The top pins of the sash will spring into the keeper recess 27 and thus, will be held against further movement. If it is desired to obtain more air, the sash C is swung further into the room and the top pins will slide in the horizontal groove 17 60 until the same ride into the keeper recess 28 which will hold the sash against further movement. In view of the fact that the sash is held tilted, a direct draft in the room will be prevented.

As shown in Figure 2 of the drawings, the top 70 sash can be slid downwardly over the top of the lower sash for the purpose of permitting more air to enter the room.

When it is desired to clean the panes of sashes, the top spring-pressed pins 38 of the lower sash 75 are forced inwardly into the sockets and the sash

is then swung to a horizontal position into the room, as shown in dotted lines in Figure 1 of the drawings. This movement is permitted in view of the bottom horizontal groove 16 and obviously, both faces of the window panes can be readily washed. 80

When it is desired to wash the upper sash, the lower sash is swung to the position shown in Figure 2 and by pressing up on the sash, the pins carried thereby can be slid into the vertical 85 groove 14 allowing the bottom sash to be disposed in rear of the top sash at the top of the window frame. The top sash B can now be slid down to its lowermost position and then swung into the room in the same manner as described 90 for the lower sash.

By my formation of the horizontal groove 16 the bottom pins of the lower sash are enabled to ride up and down and back and forth to compensate for the movement of the top pair of pins 95 within the horizontal groove 17 during the tilting of the sash.

Any preferred means can be provided for facilitating the sliding of the sashes and the same can be provided with counter-weights, if so desired. 100

As shown in Figures 1 and 2, the grooves 13 and 14 adjacent to their upper ends can be provided with keeper recesses 40 for receiving the topmost pair of the spring-pressed pins 38 when the sashes are in their raised positions. 105

From the foregoing description, it can be seen that I have provided a novel construction of window frame and sashes which will permit the convenient adjustment of the sashes for ventilating purposes and which will allow the sashes to be 110 readily moved for easy cleaning of the windows thereof without undue effort on the part of the operator.

Any desired means can be utilized with the window frames and sashes, such as weather strips 115 41 for forming a weather-tight closure for the winter season.

Changes in details may be made without departing from the spirit or scope of this invention, but what I claim as new is:— 120

A window construction comprising in combination a casing having pairs of vertical grooves at the sides thereof and a horizontal groove intercepting each pair of grooves; one groove of each pair having a lower curved extension communicating with the bottom of the other groove, said sides of the frame having short horizontal grooves communicating with the lower ends of the pairs of vertical grooves, metallic guideways of a substantially U-shape in cross section disposed in all 130 of said grooves, said metallic guideways being provided with struck-out keeper indentations arranged at spaced points in the horizontal grooves, upper and lower sashes mounted in the frame normally arranged in super-imposed relation with 135 their mating midrails in abutting relation, upper and lower spring-pressed pins carried by the opposite sides of each sash, the upper spring-pressed pins being arranged for sliding movement within the horizontal grooves for selective engagement in any of the keeper indentations, the lower pair of pins constituting pivot points for the sashes during the riding of the upper pair of pins in said horizontal grooves, the lower horizontal grooves receiving the lowermost pair of pins when the sashes are swung into a horizontal position. 140

ALBERT H. WEBER.
